FAIRING ARCH

George P. Reintjes, Kansas City, Mo.

Application September 7, 1954, Serial No. 454,465

1 Claim. (Cl. 110—99)

This invention relates to furnace arches and roofs and more particularly to constructions where roofs meet at different elevations or angles. No practical and economical means has yet been devised as far as I am aware to suspend or support a connection between two roofs of such character without the formation of an obstruction to air and gas flow which greatly reduces efficient operation.

The chief object of my invention therefore is to construct a fairing arch connecting arches or roofs which are located in different planes, in such a manner that no material abrupt offset or obstruction to smooth air or gas flow is formed, and to do this in such a way that the construction is economically sound and practical.

With the general objects named in view and others as will hereinafter appear, the invention consists in certain new and useful features of construction and organization of parts as hereinafter described and claimed; and in order that it may be fully understood, reference is to be had to the accompanying drawings, in which:

Figure 1 is a perspective view of a furnace chamber having a pair of roofs connected by a fairing arch embodying the invention.

Figure 2 is an enlarged detail to show one method of supporting the fairing arch in stepped relation.

Figure 3 is a section through the construction shown in Figure 2.

In the said drawings, where like reference characters identify corresponding parts in all of the figures, 1 are upright steel supports of a furnace chamber or the like, and said supports carry cross beams 2 spanning the furnace. The floor and walls of the furnace are respectively indicated at 3 and 4. The arrangement shown herein is by way of example and is not to be considered as a limiting factor. In the drawing 5 is a sprung arch or a suspended curved roof, and 6 is a flat roof of any type. The two roofs are not coplanar; that is, parts of one are above or below the corresponding parts of the other.

In Figure 1, the ends of the curved arch 5 are below the plane of the arch 6, and then said arch 5 curves upwardly until its center is above the plane of the arch 6. With such a construction, it is obvious that if the two arches come into abutment, there will be a flat vertical wall or obstruction at their junction. Such a flat wall offers great obstruction and resistance to the flow of air or gas and leads to turbulence and a decrease in efficient operation.

Therefore, the object of the invention is to connect the two roofs or arches in such a way that a relatively smooth unbroken contour or fairing merges one arch with the other. To be practical a construction of this kind must be economically sound, be readily repairable and subject to erection without constant engineering su-

2

pervision. To provide such a fairing arch a series of rods 7 depend from the overhead steel, said rods supporting castings 8 from which a series of spaced bolts 9 depend, the ends of said bolts being threaded into hangers 10, which by preference are of T-shape, as shown. The threaded hangers may be vertically adjusted as needed to control stepping or projection of the refractory as will hereinafter appear. The heads of the castings 10 may be received within side pockets 11 formed in the upper ends of refractory 12 to support the same as shown.

The refractory 12 is preferably of the same cross sectional area but may vary slightly in length and is preferably suspended by longer or shorter bolts 9 so that the fire or exposed ends of the refractory are stepped, whereby when erosion occurs or the stepped corners are burned off, the resulting arch is substantially of the same thickness throughout.

With the arrangement shown, where the arches or roofs 5 and 6 have sections above and below the plane of the other arch, it will be apparent that the steps must be formed in two series in right-angular relation. In other words, considering a single row of refractory in Figure 1, as a straight line from one roof to the other, the steps of the refractory on each hanger progress from the plane of one roof to the plane of the other. The next adjacent row is also stepped correspondingly to the first row, but each refractory in this series or row is stepped in relation to its companion or adjacent refractory in the same row, to compensate for the curved or bowed contour of the arch 6. Thus each set of refractory suspended from a hanger comprises a unit in two series of stepping refractory, the series or rows being in right angular relation.

From the above description it will be apparent that I have produced a construction embodying all of the features of advantage set forth as desirable, and while I have described and illustrated the preferred embodiment, it is to be understood that I reserve the right to all changes within the spirit and scope of the appended claim.

I claim:

In a chamber, a pair of roofs in vertically spaced planes, at least one of said roofs being curved transversely, a fairing arch connecting said roofs, said fairing arch comprising a series of overhead supports, hangers depending from said supports, and a plurality of refractories suspended from said hangers to form two sets of parallel rows of refractories, the first set of rows having the lower ends of the refractories progressively stepped longitudinally of one of the roofs from the plane of one roof to the plane of the other roof, and the second set of refractory rows being at right angles to the rows of the first set, the lower ends of the refractories in the rows of the second set being progressively stepped between the plane of the highest to the plane of the lowest part of the curved roof.
